Primary Examiner—Celia Murphy*Attorney, Agent, or Firm*—Marshall A. Lerner, Esq.; Bradford E. Mattes, Esq.; Kleinberg & Lerner, LLP**[57] CLAIM**

The ornamental design for a combined shoe bottom and periphery as shown and described.

DESCRIPTION

FIG. 1 is a perspective view of the right, front and bottom of a combined shoe bottom and periphery showing my new design;

FIG. 2 is a bottom plan view thereof;

FIG. 3 is a right side elevational view thereof;

FIG. 4 is a left side elevational view thereof;

FIG. 5 is a front side elevational view thereof; and,

FIG. 6 is a rear elevational view thereof.

The broken line showing the shoe upper in the figures is for illustrative purposes only and forms no part of the claimed design. The portion of the surface left unshaded in FIG. 5 is not part of the claimed design.
